United States Patent Office

Des. 180,591

Patented July 9, 1957

180,591

ELECTRIC HAND SAW

Robert O. Ernest and Ivar Jepson, Oak Park, Ill., assignors to Sunbeam Corporation, Chicago, Ill., a corporation of Illinois

Application July 18, 1956, Serial No. 42,289

Term of patent 14 years

(Cl. D93—3)

Fig. 1 is a perspective view of an electric hand saw embodying our invention;

Fig. 2 is a side elevational view of the electric hand saw of Fig. 1;

Fig. 3 is a front elevational view of Fig. 2;

Fig. 4 is a top plan view of Fig. 2;

Fig. 5 is a bottom plan view of Fig. 2; and

Fig. 6 is a rear elevational view of Fig. 2.

We claim:

The ornamental design for an electric hand saw, as shown.
